J. R. GREEN

KEYED ZITHER,

APPLICATION FILED MAY 16, 1916. RENEWED FEB. 25, 1919.

1,299,704.

Patented Apr. 8, 1919.

UNITED STATES PATENT OFFICE.

JOSEPH R. GREEN, OF WAKEFIELD, MASSACHUSETTS, ASSIGNOR TO THE PHONOHARP COMPANY, OF EAST BOSTON, MASSACHUSETTS, A CORPORATION OF MAINE.

KEYED ZITHER.

1,299,704.

Specification of Letters Patent.

Patented Apr. 8, 1919.

Application filed May 16, 1916, Serial No. 97,829. Renewed February 25, 1919. Serial No. 279,179.

To all whom it may concern:

Be it known that I, JOSEPH R. GREEN, a citizen of the United States, residing at Wakefield, in the county of Middlesex and State of Massachusetts, have invented new and useful Improvements in Keyed Zithers, of which the following is a specification.

This invention relates to stringed musical instruments and particularly to playing devices for such instruments. U. S. patent to Marx, 1,044,553, granted November 19, 1912, discloses playing devices each comprising a flexible spring shank, and a head carried thereby for striking the wires or strings, the flexible spring shank being arranged to cause the head to strike a series of blows in rapid succession when depressed once, to produce the effect of a mandolin. The present invention relates particularly to playing devices of the character mentioned, but in the present instance the specific form of playing device is like that shown in Letters Patent to Marx 1,190,783. Hitherto these playing devices have been used to sound the melody strings and have not been arranged to sound chords excepting that three or more of them could be depressed simultaneously to sound a chord on the melody strings.

Some, if not all, instruments of the character mentioned are provided with chord-producing strings or wires arranged in groups, in addition to the melody strings, and although playing devices have been provided for playing on the melody strings, chord-playing devices have not been provided for sounding chords on the groups of chord-producing strings. The present invention includes a stringed instrument having melody strings and playing devices therefor, and groups of chord-producing strings and chord-playing devices each arranged to coact with all the chord-producing strings or wires of the group with which it is associated. In the use of such an instrument the melody-playing devices may be operated with the fingers of one hand to sound the melody notes one by one, and the chord-playing devices may be operated with the fingers of the other hand to play an accompaniment for the melody, the actuation of a single chord-playing device by one finger being all that is necessary to produce a chord. The possibility of playing a chord with one finger is due to the fact that all the chord-playing strings or wires of a

given chord group are within range of action of a single playing device and are struck simultaneously by such device when the latter is depressed. The playing of a chord is therefore no more difficult or complicated than the playing of a single note of the melody.

According to the specific embodiment of the invention as shown by the accompanying drawings, the chord-playing devices, as well as the melody-playing devices, have spring shanks adapted to cause a series of blows in rapid succession as the result of simply depressing the playing device once, but for reasons that are hereinafter fully explained I prefer to make the spring shanks of the chord-playing devices substantially shorter than those of the melody-playing devices, to the end that the period of striking will not last so long as in the case of the melody-playing devices. The shorter duration of the active period of the chord-playing devices avoids the tendency of the chord-producing strings to "drown" the melody.

Of the accompanying drawings:

Figure 1 represents a top plan view of a stringed musical instrument embodying this invention.

Fig. 2 represents a side elevation thereof.

Fig. 3 represents a vertical section through the chord-playing mechanism.

Fig. 4 represents a sectional view, in conventional form, including four strings or wires of a chord-producing group, and the head of the striker that cooperates with them.

The same reference characters indicate the same parts wherever they occur.

The base or body of the instrument includes a sounding board 10 and a bottom piece 11, the space between said elements being the sound-box. The strings or wires are arranged in two main groups, those of one group being hereinafter termed melody strings, and those of the other main group being hereinafter termed chord-producing strings. The main group of chord-producing strings is divided into sub-groups, each of which comprises the strings of one chord. In the present instance there are four chord-producing strings in each sub-group, and they are indicated individually at a' , a^2 , a^3 and a^4 . It will be noted that string a' of each sub-group is relatively large in di-

ameter, this being the bass string of each chord. The melody strings are indicated at *b*, and in the present instance there are two strings for each note.

- 5 Although the playing devices are, in principle, substantially like those illustrated and described in the said patent to Marx, 1,190,783, a brief description may be given for present purposes. Each playing device comprises a spring shank 12, a relatively stiff rocking holder 13 therefor, and a head 14 affixed to the outer end of the shank. The several holders 13 are arranged side by side upon the upper edge 15 of a support or fixture 16. Each holder is provided with a notch 17 into which the support extends, and the holders are confined with freedom to tilt, by an overhanging fixture 18. As shown by Fig. 3, the right-hand end of the flexible spring shank 12 is bent downwardly and engages the fixture 16. The shank has to be flexed from its normal position in order to place it in this position, and it continually tends to elevate the head 14. A pad 19 of soft cushioning material, such as felt, is arranged to overlie the heads 14 and limits upward movement of the heads. This pad is supported by a holder 20 which in turn is supported by a pair of flexible spring shanks 21, 21 substantially like the shanks 12.
- In all the particulars so far described the chord-playing devices and melody-playing devices are similar, but there are differences that will be explained. The shanks 12 of the chord-playing devices are substantially shorter than those of the melody-playing devices, the difference in length being shown most clearly by Fig. 2. This difference in length causes the heads of the chord-playing devices to vibrate much more rapidly than those of the melody-playing devices, and limits the period of activity of the chord-playing devices to a shorter time than that of the melody-playing devices. The phrase "period of activity" does not mean the period of vibration, but means the period during which the device operates upon the strings. The chord-playing devices are provided with raised finger-pieces 22, but the melody-playing devices are shown without them. The head 14 of each chord-playing device coacts with all the strings *a'*, *a²*, *a³* and *a⁴* of a chord-group, as shown by Figs. 1 and 4; and although the head of each melody-playing device coacts with two strings *b* it does not produce more than one tone, because, according to the arrangement of the melody strings, each pair will be tuned to the same pitch and will be as one in tone but will have greater volume than one. The heads of the chord-playing devices are cut away, as indicated at *x* in Figs. 3 and 4, to compensate for difference in diameter between the bass

string *a'* and the smaller strings *a²*, *a³* and *a⁴*, for although the centers of the strings are all approximately in one plane, the tops of the strings are out of plane because of the difference in diameter. The cutting 70 away at *x* therefore avoids the undesirability of striking the base string with greater force than the three smaller strings.

Referring to Fig. 3,—the playing device is shown in its normal position by solid 75 lines. When the raised finger-piece is depressed it takes the position indicated by dotted lines, and the momentum acquired by the head 14 causes the spring shank 12 to be flexed downwardly after the downward 80 movement of the finger-piece and holder 13 has been arrested by the fixture in which they are mounted. Abnormal flexure of the spring shank thus enables the head to impinge against the wires, but the head immediately rises to the highest dotted-line position in consequence of the recoil of the spring shank and of the strings. After two or three impacts against the strings the range of vibration of the head is so far diminished 85 that it does not come in contact with the strings again although it may vibrate indefinitely until the spring shank assumes its normal position, which in Fig. 3 is the intermediate dotted position. This normal position 90 is indicated also in Fig. 2, and the corresponding normal depressed position of a melody-playing device is also represented by dotted lines in Fig. 2. By comparing the normal depressed positions of the two playing devices in Fig. 2 it will be seen that the head of the melody-playing device is much closer to the general plane of the strings than is the head of the chord-playing device. This closer proximity of the head of the 100 melody-playing device, in conjunction with the greater length of the shank, gives the melody-playing device a longer period of activity than that of the chord-playing device. Consequently, assuming that a chord-playing device and a melody-playing device are depressed simultaneously with equal force, they will begin to sound their respective strings at approximately the same instant, but the period of activity of the melody-playing device will continue after that 105 of the chord-playing device ceases. The said difference in proximity and in the length of shank enables the melody-playing device to strike its strings with greater force than that 110 of the chord-playing device, and thus, although four chord-producing strings are capable of producing a greater volume of sound than two melody strings, the more forcible impact of the melody-playing device 115 tends to equalize the volume as between the two sets of strings.

Another result of the difference in shank length is this:—The vibrations of the shorter shank are so rapid that they are in effect 120

merged into one sustained note, whereas the comparatively slow vibrations of the longer shank produce noticeable articulation. The slower rate of vibration thus gives more 5 prominence to the melody than the latter would have if the spring shanks of the two sets of playing devices had the same frequency of vibration.

Referring to Figs. 1 and 2, it will be noted 10 that the chord-playing devices are offset from alinement with the melody-playing devices, and leave the chord-producing strings exposed at the left of the melody-playing devices, so that if the player desires a softer 15 accompaniment than that produced by the chord-playing devices he may produce the same by picking the chord-producing strings with the fingers.

I claim:

- 20 1. A stringed musical instrument having a plurality of playing devices arranged to act upon the strings, each of said playing devices comprising a spring shank and a string-engaging head carried thereby, some of said shanks being longer than others in order to have greater note-sustaining capacity.
- 25 2. A chord-playing device for a stringed

musical instrument having groups of chord-strings of different diameters with the axes of the several strings in the same plane, said 30 device comprising a spring shank and a string-engaging head carried thereby, the string-engaging surface of said head having a stepped formation adapted to compensate for the difference in diameter of the strings 35 to be engaged thereby.

3. The combination with a stringed musical instrument having melody strings, manually operable playing devices arranged to coact therewith, each of said melody-playing devices having a spring shank and a string-engaging head carried thereby, and chord-producing strings arranged in chord groups; of chord-playing devices arranged to coact respectively with said groups of 45 strings, each of said chord-playing devices comprising a spring shank and a string-engaging head thereon, the spring-shanks of said chord-playing devices being substantially shorter than those of said melody- 50 playing devices.

In testimony whereof I have affixed my signature.

JOSEPH R. GREEN.
